Primary Examiner — Rosemary K Tarcza*Assistant Examiner* — Seth David Kumpf(74) *Attorney, Agent, or Firm* — Taylor IP, P.C.**CLAIM**

The ornamental design for a power tap electrical receptacle, as shown and described.

DESCRIPTION

FIG. 1 is a perspective view of a power tap electrical receptacle showing my new design;

FIG. 2 is a top plan view thereof;

FIG. 3 is a bottom plan view thereof;

FIG. 4 is a side view thereof, the opposite side view being a mirror image thereof;

FIG. 5 is a first end view thereof; and,

FIG. 6 is a second end view thereof, the second end view being opposite to the first end view.

In the drawings, the broken lines are for the purpose of illustrating portions of the article that form no part of the claimed design.

1 Claim, 2 Drawing Sheets(56)
